UNITED STATES PATENT OFFICE.

JOHN DANIEL METTLER, OF SNYDERTOWN, PENNSYLVANIA.

DUMP-CAR.

1,092,659.

Specification of Letters Patent.

Patented Apr. 7, 1914.

Application filed July 14, 1913. Serial No. 778,941.

To all whom it may concern:

Be it known that I, JOHN DANIEL METTLER, a citizen of the United States, and a resident of Snydertown, in the county of 5 Northumberland and State of Pennsylvania, have made certain new and useful Improvements in Dump-Cars, of which the following is a specification.

My invention relates to improvements in 10 dump cars, more especially in those designed to be used for hauling and dumping coal, and it consists in the combinations, constructions and arrangements herein described and claimed.

15 An object of my invention is to provide a car of the type described having hinged bottom portions which may be easily moved to effect the dumping of the contents of the car, and which may be readily secured to 20 hold the load without any danger of dumping the same in transit.

A further object of my invention is to 25 provide a device having means for draining water from the load and at the same time preventing leakage of portions of the material which is being transported.

30 A further object of my invention is to provide a device which dispenses with ratchets or the use of wrenches for operating the doors, thereby obviating the danger of injury from a flying wrench or other tool when the doors are operated.

35 A further object of my invention is to provide a device of the type described in which the doors may be operated from either side of the car.

40 Other objects and advantages will appear in the following specification and the novel features of the device will be particularly pointed out in the appended claims.

My invention is illustrated in the accompanying drawings forming part of this application in which—

45 Figure 1 is a plan view of the device, Fig. 2 is a section along the line 2—2 of Fig. 1 looking in the direction of the arrows, Fig. 3 is a section along the line 3—3 of Fig. 1 looking in the direction of the arrows, Fig. 4 is a perspective view of one 50 of the movable doors, Fig. 5 is a section along the line 5—5 of Fig. 3. Fig. 6 is a side view of one of the operating links, Fig. 7 is a perspective view of a retaining

yoke, and Fig. 8 is a section on the line 8—8 of Fig. 1 looking in the direction of the 55 arrow.

In carrying out my invention I provide a frame consisting of the longitudinal side members 1 and 1', the parallel longitudinal members 2 and 2' disposed near the center 60 of the device and the cross members 3 and 3'. As will be seen from Fig. 1 the frame is divided by the cross members 3 and 3' into four divisions corresponding to four compartments. Secured to the cross members 3 and 3' are triangular shaped end plates 4 and 4' respectively. A bottom plate is provided for each compartment such as those shown at 5 and 5' having end flanges 5* arranged to extend outside of and secured to the end members 4 (or 4'). These bottom plates are secured to the longitudinal members 2 or 2' by means of brace members 6 and 6' respectively. These brace members serve the double purpose of securing means 65 and also of strengthening members for the bottom plates.

Referring now to Fig. 1 it will be seen that I have provided the longitudinal rods 7 and 7' which extend through the end members 4 and 4' (see Fig. 3) and which are also supported at intervals by L-shaped brackets 8 and 8'. These rods form pivot members for the doors. The latter are preferably of the shape shown in Fig. 4. A description of one of the doors will suffice since they are all alike.

Referring to Fig. 4 it will be seen that I have provided longitudinal members 9^a and 9^b, these members being disposed in angular relation and being integral to form a body portion having a substantially V-shaped cross section, the member 9^b being greater in width than the member 9^a. Integral end portions 9^c are provided. The longitudinal members 9^a and 9^b are strengthened 90 by transverse brace members 9^d, similar to the brace members 6 and 6'. Extending longitudinally of the device where the bend in the V occurs is a slot 9^e which permits the drainage of the contents of the compartment. On the outer side of each door is a V-shaped trough 10 which is secured to the door and which has a portion spaced from the door so as to carry off the water which has passed 100 through the slot 9^e. Secured to the mem-

ber 9^b is a series of loops 9^c by means of which the door is pivotally suspended from the rod 7 (see Fig. 2). On the under side of each door portion 9^c is a rod 9^e which extends longitudinally of the door and to each end of which is secured an operating arm like that shown in Fig. 6. As will be seen from Figs. 1 and 6, the rod 9^e is provided with an eye through which the threaded end 10 11^a of the operating arm 11 extends. Nuts 11^b are provided for adjusting the position of the arm 11 with respect to the rod 9^e. The rod or arm 11 is provided with a bend 11^c whose purpose will be explained later. 15 It is also provided at one end with a slot 11^d. Referring now to Figs. 1 and 8 I have shown two longitudinally extending rock shafts 12 and 12' disposed underneath the doors. These rock shafts are rotatably supported by means of enlarged cylindrical bearing portions 12^x or in any other suitable manner in end plates 13 which have upwardly extending central portions 13^a secured to the central longitudinal frame members 2 and 2' (see Fig. 8). The rock shafts 12 and 12' have secured to them just outside the ends of the compartments, arms 14 which are pivotally connected to the arms or links 11 by means of bolts or pins 15 which pass 20 through the slots 11^d (see Fig. 6).

Referring again to Figs. 1 and 3 it will be seen that I have provided downwardly extending brackets 16 which are secured to the side members 1 and 1' of the frame, and 25 upon which is rotatably mounted a shaft 17 extending transversely of the device. Hand wheels 18 are secured to the ends of the shaft 17. The center of the shaft 17 is from the central frame members 2 and 2' by means 30 of a yoke 19. The shaft 17 bears worms 20 and 20' arranged to engage gears 21 and 21' mounted upon the rock shafts 12 and 12' respectively. In order to hold the worms in mesh with the gears I provide a yoke like 35 that shown in Fig. 7. This yoke has a body portion 22 having an opening 22^a to receive the shaft 17 and being provided with laterally extending portions 22^b having aligned openings 22^c to receive the cylindrical bearing members 12^y of the rock shafts 12 and 12' respectively. This insures the engagement 40 of the worms with their respective gears. The sides 24 of the car attach directly to the outer frame members 1 and 1', 45 as shown in Figs. 2 and 3.

From the foregoing description of the various parts of the device the operation thereof may be readily understood.

The compartments which are closed by 50 the V-shaped doors are designed to be loaded with coal or any other suitable material. The provision of the slots 9^e provides means for draining the compartments of any water which may collect therein, this water pass-

ing through the slots 9^e and being carried 55 away by the troughs 10. At the same time the provision of the troughs prevents escape of material or leakage of the material. When the car is loaded the position of the mechanism for holding the doors in their 60 closed position is that shown in full lines in Figs. 2 and 3. It will be noted that in this position the bent portions 11^c of the links or arms 11 are in such a position as to take over the rock shafts 12 and 12'. This 65 holds the doors tight against the stationary portions 5 and 5' forming part of the bottom of the compartment. Now when it is desired to dump the car one of the hand wheels 18 on either side of the car is turned. 70 This, through the medium of the shaft 17, worms 20 and 20', and gears 21 and 21', will cause the rotation of the rock shafts 12 and 12' in opposite directions, since one of the 75 worms is a right hand screw and the other is a left hand screw. This will cause the rotation of the arms 14 so as to cause the links or arms 11 to move from the full line position shown in Fig. 2 to the dotted line position, 80 thus forcing open the doors into the position indicated in dotted lines in Fig. 2 and permitting the contents of the car to be dumped. In order to close the doors again 85 the hand wheels 18 are rotated in the opposite direction. The purpose of the slots 11^d 85 in the links or arms 11 is to permit the bent portions of the rods 11 to be brought down into engagement with the rock shaft 12. It will be noted that as the rock arms 14 are 90 turned the pins 15 will be moved from one end of the slot to the other. This movement permits of the turning of the hand wheels 18 so as to bring the doors firmly 95 against the stationary bottom portion of the compartments thus preventing any leakage 100 and holding the doors securely in place.

It will be noted that the doors are so formed that they inclose the end members and the stationary portion 5 of the bottom of the compartment. The compartments are 110 thereby made proof against leakage or waste. The provision of the worm and gear not only provides great power for closing and opening the doors, but acts as a positive locking member for these doors since it is 115 impossible to open them by pressure on the inside of the compartment. The only means to open them is to turn the hand wheels 18. The position of the links or arms 11 with respect to the doors may be 120 adjusted by means of the nuts 11^b so that the doors may be brought into close contact with the stationary bottom members 5, thereby insuring the proper closing of the doors. Thus when the member 11 is thrown 125 to the closed position if the door should not be quite shut the nuts 11^b may be tightened so as to bring the door in close contact with

the stationary bottom members 5. It is obvious that when this adjustment is once made the door will be securely closed each time the member 11 is operated. If at any time, through strain or otherwise, there should be any play between the door and the bottom member 5, this play may be again taken up by adjusting the nut.

The frame composed of the members 1, 2, 10 3 and 1', 2', and 3' may be supported upon any suitable form of truck.

While I have illustrated the car as being composed of four compartments having doors operated simultaneously by a hand 15 wheel on either side of the car it will be understood that more or less compartments may be provided than those shown without departing from the spirit and the scope of the invention.

20 One feature to which I desire to call particular attention is the fact that when the doors are closed by means of the links or arms 11 the latter are brought to rest upon the rock shafts 12. Thus the weight of the 25 door is supported to a large extent by these rock shafts which are securely fastened in the frame. There is therefore little danger of the door giving way under the weight of the load above it.

30 I claim:

1. In a dump car, a frame, a compartment therein provided with stationary ends of triangular shape, a stationary bottom member secured to said frame and to said 35 ends, a door of V-shaped cross section arranged to swing into engagement with the under side of said stationary section, said door having end flanges arranged to inclose said end sections, and means for operating 40 said door, said last named means comprising an arm pivotally connected with said link, a rock shaft, a rock arm carried by said rock shaft and having a pivotal connection with said link, and means for rotating said 45 rock arm.

2. In a dump car, a frame, a compartment therein provided with stationary ends of triangular shape, a stationary bottom member secured to said frame and to said 50 ends, a door of V-shaped cross section arranged to swing into engagement with the under side of said stationary section, said door having end flanges arranged to inclose said end sections, means for operating 55 said door, said last named means comprising an arm pivotally connected with said link, a rock shaft, a rock arm carried by said rock shaft and having a pivotal connection with said link, means for rotating 60 said rock arm, including a rotatable shaft, a worm carried by said rotatable shaft, and a gear carried by said rock shaft and arranged to be engaged by said worm.

3. In a dump car, a frame, a compartment

therein provided with stationary ends of 65 triangular shape, a stationary bottom member secured to said frame and to said ends, a door of V-shaped cross section arranged to swing into engagement with the under side of said stationary section, means for operating 70 said door, said means comprising a link pivotally connected with said door, a rock shaft, a rock arm connected with said rock shaft and having pivotal connection with said link, and means for rotating said rock 75 shaft to bring the link into engagement with the said rock shaft when the door is closed, thereby bringing the weight of the door on the link and the rock shaft.

4. In a dump car, a frame, a plurality of 80 compartments carried by said frame, each of said compartments having stationary end members of triangular shape, stationary bottom members secured to said end members and to said frame, a hinged door for 85 each compartment, said hinged door having a V-shaped cross section, means for bringing all of said doors into engagement with their respective stationary bottom members and locking them in their closed positions, 90 said means comprising a pair of parallel rock shafts, links pivotally connected with each of said doors, rock arms carried by said rock shafts and having pivotal connection with each of said links, and means 95 for rotating said rock shafts simultaneously in opposite directions.

5. In a dump car, a frame, a plurality of compartments carried by said frame, each of said compartments having stationary end 100 members of triangular shape, stationary bottom members secured to said end members and to said frame, a hinged door for each compartment, said hinged door having a V-shaped cross section, means for bringing all of said doors into engagement with their respective stationary bottom members and locking them in their closed positions, 105 said means comprising a pair of parallel rock shafts, links pivotally connected with each of said doors, rock arms carried by said rock shafts and having pivotal connection with each of said links, means for rotating said rock shafts simultaneously in 110 opposite directions, said last named means comprising a rotatable shaft arranged to extend transversely of said rock shafts, a gear on each of said rock shafts, a right hand screw on said rotatable shaft arranged to engage one of said gears, and a left hand 115 screw on the rotatable shaft arranged to engage the other of said gears.

6. In a dump car, a frame, a compartment carried thereby having stationary end members, a stationary bottom member secured 125 to said end members, a swinging door arranged to engage said stationary bottom member, said door being of V-shaped cross

section and constituting part of the compartment, a rock shaft disposed underneath said door, a rock arm for said rock shaft, and a link pivotally connected with said door and having a pivotal connection with said rock arm, said link having a bent portion arranged to take over and rest upon

said rock shaft, thereby bringing the weight of the door on the link and the rock shaft.

JOHN DANIEL METTLER.
